UNITED STATES PATENT OFFICE.

THOMAS DANQUARD, OF NEW YORK, N. Y., ASSIGNOR TO AUTO PNEUMATIC ACTION COMPANY, A CORPORATION OF NEW YORK.

NOTE-SHEET-TRACKING DEVICE.

1,255,296.

Specification of Letters Patent.

Patented Feb. 5, 1918.

Application filed August 25, 1911. Serial No. 646,054.

To all whom it may concern:

Be it known that I, THOMAS DANQUARD, a citizen of the United States, residing at New York, in the county of New York and State 5 of New York, have invented a new and useful Note-Sheet-Tracking Device, of which the following is a specification.

The object of this invention is to provide a new and improved device for keeping the 10 perforated note sheet employed in connection with the tracker bar in musical instruments and similar devices automatically in proper registration.

To this end the invention consists in providing a single guide opening and two pneumatic motors, which are arranged to operate in one direction when the guide opening is covered, and in the other direction when the guide opening is uncovered, said motors 20 being connected to adjust the relation between the note sheet and tracker, and therefore to keep the note sheet in proper registration with the tracker bar within the limits of the covering and uncovering of the 25 guide opening.

The invention also consists of the parts and combinations of parts hereinafter described.

The invention is illustrated in the accompanying drawing, referring to which—

Figure 1 is a front elevation partly in section of the preferred form of my device;

Fig. 2 is a plan; and

Fig. 3 a front elevation of a modified arrangement.

Referring to the drawing, and in detail, A designates the tracker; B the perforated note sheet; C the spool or roll on which the note sheet is wound; and D the drawing roll 40 which is actuated by any suitable gearing to draw the note sheet over the tracker. These parts are arranged in a frame and the music spool is held in bearings and normally pressed to the right by a spring 10 and engaging plunger 11. These parts are arranged in the ordinary way and need no further description.

The tracker is provided with a single guide opening 12, which is arranged to come 50 just at the edge of the note sheet when the same is in normal position laterally on the

tracker. This guide opening 12 is preferably made narrow and long. This guide opening communicates by a tube 13 with a pneumatic adjusting mechanism arranged 55 as hereinafter described. The tube 13 connects with a valve casing X, and under a diaphragm 14 arranged therein. This diaphragm is arranged to operate a double valve 15—16, which double valve controls 60 the flow of air into and out through passage 17. The valve casing X is arranged on a block E secured to which are two pneumatic motors F and G connected to operate together by a link 18. A chamber is formed 65 in the center of this block E, and arranged in the same is a pneumatic H, one side of which is secured to the block E and the other side of which is free to swing on the hinge 19 of the pneumatic H. 70

A spring 20 is arranged normally to force the movable leaf of the pneumatic to the right. A passage 21 is formed in the block E to form a continuation of the passage 17, and the passage 21 communicates with the 75 inside of the pneumatic H. The chamber in the inside of the block E is connected to the vacuum inducing apparatus of the instrument by a pipe 22, and this chamber communicates with the space above the diaphragm 14 by a passage 23.

A passage 24 extends upwardly from each pneumatic motor F and G into a horizontal passage 25 communicating both with the said chamber and the atmosphere. Coöperating with each passage 25 is a double valve 26—27. The movable leaf 19 of the pneumatic H is provided with an arm 28 which extends between the valves 26. The righthand pneumatic motor G connects by 90 link 29, pivoted bell-crank 30, link 31, arm 32, shaft 33, and cam 34 to operate the plunger or socket piece 35 which holds the right hand end of the music spool C. 85

In operation the right hand edge of the 95 music sheet will just cover or uncover the narrow guide opening 12. As shown, the music sheet has just been moved to cover the guide opening 12. This will allow the diaphragm 14 and the double valve 15—16 to 100 drop, which will connect the pneumatic H to the exhaust through the passages 17 and

21. The spring 20 will now force the movable leaf 19 of the pneumatic H to the right. The double valves 26 and 27 are normally pulled inwardly by the exhaust in the chamber in the block E, so that both pneumatic motors F and G normally will be open to the exhaust in said chamber and thereby balanced. As the pneumatic H collapses, the right hand double valve 26-27 will be moved to the position shown, which will allow atmospheric air to enter the right hand pneumatic motor G. This will cause the movable leaf of this pneumatic motor to move to the right, which, through the connections described, will move the music spool C to the left and uncover the guide opening 12.

As soon as the guide opening 12 is uncovered, atmospheric air will flow through 20 the same and through tube 13 under diaphragm 14. This will lift the double valve 15-16 and allow atmospheric air to flow through passages 17 and 21 into the pneumatic H, which will cause the movable leaf 25 of the same to swing to the left, which will allow the right hand double valve 26-27 to assume its normal position, but will move the left hand double valve 26-27 outwardly and connect the left hand pneumatic motor 30 F to the atmosphere. This will cause the movable leaf of the left hand pneumatic motor F to move to the left, which, through the connections described, will cause the music spool C to move to the right under 35 the tension of the spring 10, which will cause the note sheet to move to cover the guide opening 12. This covering and uncovering of the guide opening 12 will take place very quickly, and will cause a slight 40 fluttering action of the pneumatic motors and a slight fluttering action of the note sheet, but this fluttering action will be restrained to very slight limits, and by this operation the note sheet will be guided in 45 its travel in proper relation across the tracker bar.

As previously stated, both pneumatics F and G normally are open to the exhaust and thereby balance each other. The normal 50 position of the note-sheet B on the tracker A is when the note-sheet slightly uncovers the guide opening 12 so that a slight volume of atmospheric air will flow through pipe 13 under diaphragm 14, and 55 by reason of the bleed, will cause said diaphragm lightly to bear on the double valve 15 and 16 so as partially to lift the same to allow a suction around the valve 15 and also a flow of atmospheric air around valve 60 16 into passage-way 17 so as to cause such pressure in the pneumatic H as to allow the movable leaf thereof to move far enough to the left against the pressure of the spring 20 to cause the arm 28 to come to central 5 position between the two double valves

26-27 so that they will assume the same position relatively to the openings controlled thereby, whereby the same tension will be exerted in both bellows motors F and G.

In short, in normal position, the note-sheet will partially cover the guide opening 12 and will allow a slight bleed or rush of atmospheric air therethrough, which by reason of the valve constructions, will hold the two bellows motors in balanced condition. 75

In Figs. 2 and 3 a modification is shown which consists in employing the edge of the note sheet to cover and uncover the guide opening instead of the surface of the note sheet. In this arrangement the guide opening 12 is formed in a block 36 secured to the frame, and is controlled by a pivoted valve 37 which is actuated by pivoted lever 38 which is pressed to the left by a light spring 39, and which connects by a link 40 to said pivoted valve 37. The lever 38 extends through a hole 41 formed in the tracker bar in position to engage the edge of the sheet. This modification works the same as the device previously described, except that 80 the covering and uncovering of the guide opening is effected by the edge instead of the surface of the sheet. 85

It will be noted that the music sheet is guided entirely by one edge, which is desirable, as this will eliminate difficulties arising from expansion and contraction of the sheet and variations in the width thereof. 90

It is within the scope of my invention to connect the pneumatic motors to shift the 100 tracker instead of the note sheet.

Many other modifications may be worked out for practising my invention without departing from the scope thereof as expressed in the claims. 105

Having thus fully described my invention, what I claim is:—

1. The combination of a tracker, means for drawing a note sheet across the tracker, a single guide opening, two pneumatic motors for adjusting the lateral relation of the note sheet and tracker, a valve controlled by said guide opening, a pneumatic controlled by said valve, and valves operated by said pneumatic for controlling the motor 110 pneumatics. 115

2. The combination of a tracker, means for drawing a note sheet across the tracker, a single guide opening, two pneumatic motors for adjusting the lateral relation of 120 the note sheet and tracker, a double valve controlled by said guide opening, a pneumatic controlled by said double valve, and two double valves controlled by said pneumatic for controlling the operation of the 125 two motor pneumatics.

3. The combination of a tracker, means for drawing a note sheet across the tracker, a single guide opening, two motor pneumatics for adjusting the lateral relation of 130

the note sheet and tracker, a double valve controlled by said guide opening, a spring-pressed pneumatic controlled by said double valve, and double valves controlled by said 5 spring-pressed pneumatic for controlling the action of the two motor pneumatics.

In testimony whereof I have hereunto set

my hand, in the presence of two subscribing witnesses.

THOMAS DANQUARD.
